TOY CEMENT MIXER

Robert Genin, Scarsdale, N.Y., assignor to Child Guidance Toys, Inc., New York, N.Y., a corporation of New York

Filed Apr. 5, 1967, Ser. No. 6,532

Term of patent 14 years

(Cl. D34—15)

FIG. 1

FIG. 2

FIG. 3

FIG. 4

FIG. 1 is a perspective view of my design for toy cement mixer having a transparent barrel and a transparent body;

FIG. 2 is a front view of the toy cement mixer;

FIG. 3 is a plan view of the toy cement mixer, toy balls contained in the barrel being visible therethrough; and

FIG. 4 is a side view of the toy cement mixer, the operating gears being visible through the transparent body.

I claim:

The ornamental design for a toy cement mixer, substantially as shown and described.
